This invention relates to head shields and, more particularly, to head shields having means for cooling the interior of the device by the introduction of air, thereby greatly promoting comfort.

UNITED STATES PATENT OFFICE

2,354,502

HEAD SHIELD

William T. Cockrill and Thomas J. Duncan,
Flint, Mich.

Application April 21, 1943, Serial No. 483,928

3 Claims. (Cl. 2-8)

The present invention relates to new and useful improvements in head shields for use particularly in arc welding, grinding, painting, etc., and has for its primary object to provide, in a manner as hereinafter set forth, a device of this character comprising a hood which includes a novel combination and arrangement of hinged eye protectors, either or both of which may be conveniently swung open to inoperative position when desired.

Another very important object of the invention is to provide a head shield or hood of the aforementioned character comprising unique means for cooling the interior of the device by the introduction of air, thereby greatly promoting comfort.

Other objects of the invention are to provide a shield of the character described which will be comparatively simple in construction, strong, durable, compact, light in weight and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein—

Figure 1 is a view in side elevation of a shield constructed in accordance with the present invention, portions of the device being broken away in section.

Figure 2 is a view in front elevation of the device.

Figure 3 is a view in vertical section through the front portion of the device.

Figure 4 is a fragmentary view in bottom plan.

Figure 5 is a fragmentary view in rear elevation of the fabric portion of the hood.

Referring now to the drawings in detail, it will be seen that the embodiment of the invention which has been illustrated comprises a hood 1 to receive the head of the mechanic. The hood 1 includes a fiber front 2 having mounted thereon a flexible back 3 of suitable fire resisting fabric. An adjustable head band 4 is mounted in the upper portion of the front 2 of the hood 1 for supporting said hood on the head.

The front 2 of the hood 1 has formed therein an opening 5 of suitable dimensions. Mounted on the front 2 around the opening 5 is a metallic frame 6 the side and bottom members of which are angular in cross section, said frame including a flat upper bar 7.

Suspended from the bar 7 of the frame 6 for

closing the opening 5 in the hood front 2 is an eye protector 8 comprising an amber glass 9. Hinges 10 and 11 secure the protector 8 to the bar 7 of the frame 6, said hinge 11 including a spring 12 which yieldingly urges the inner protector 8 downwardly to closed or operative position over the opening 5.

Hingedly mounted on the protector 8 is an outer protector 13. The outer protector 13 includes a metallic plate 14 which is suspended by spring hinges 15 on the upper portion of the inner protector 8. The spring hinges 15 yieldingly urge the outer protector 13 upwardly toward open or inoperative position. The metallic plate 14 has formed therein an opening or window 16 over which filter glasses 17 are mounted. A latch 18 on the lower portion of the hood front 2 releasably secures the outer shield 13 in closed or operative position on the inner shield 8.

Secured by clips or the like 19 in the upper portion of the hood 1 is an air hose 20 which may be connected to any convenient source of supply. The air hose 20 enters the hood 1 through the flexible back 3 thereof. At its forward end, the air hose 20 terminates in discharge branches 21 which are arranged to direct the air downwardly over the eyes of the mechanic.

A strip of heavy fabric 22 is riveted or otherwise suitably secured to the marginal portions of the front 2 of the hood 1, said strip having mounted thereon buttons 23. The back 3 of the hood 1 includes overlapping half sections 24 which are buttoned together at 28 and which are secured to the front 2 by the buttons 23. The lower portions of the members 2 and 3 are shaped to accommodate the neck of the mechanic. Toward this end, the lower edges of the fabric sections 24 are provided with hems 25 which enclose elastic bands or straps 26. The elastic bands 26 contract or gather the lower portions of the fabric hood sections 24 snugly about the neck of the mechanic.

In use, when the mechanic is welding, the inner and outer protectors 8 and 13 are both in lowered or operative positions over the opening 5 in the front 2 of the hood 1. When the weld has been made, and the mechanic desires to grind off flashings from the weld, he simply disengages the latch 18 from the lower or free end of the door or plate 14 for permitting the spring hinges 15 to swing the outer protector 13 upwardly to raised or inoperative position, leaving the inner protector 8 in operative position to function as a goggle. When, for any reason, the mechanic desires access to his face or nose, he may con-

veniently swing the inner protector 8 upwardly to raised or inoperative position. In addition to promoting comfort by lowering the temperature within the hood 1, the discharge of air from the hose 20 prevents fogging of the glass 9, thereby speeding production. The air which enters the hood 1 under pressure, escapes through and around the fabric back 3 of said hood. A handle 27 is provided to facilitate opening the inner protector 8.

It is believed that the many advantages of a head shield constructed in accordance with the present invention will be readily understood and although a preferred embodiment of the device is as illustrated and described, it is to be understood that changes in the details of construction and in the combination and arrangement of parts may be resorted to which will fall within the scope of the invention as claimed.

Having described the invention, what is claimed as new is:

1. A head shield of the character described comprising a hood having an opening in the front thereof, an inner protector hingedly suspended on the hood over the opening, and an outer protector hingedly mounted on the inner protector, said outer protector including a plate having an opening therein, and filter glasses mounted on said plate over the opening.
2. A head shield of the character described comprising a hood having an opening in the front

thereof, a metallic frame on the hood around the opening, an inner protector comprising a glass, hingedly suspended in the frame and engageable with the hood over the opening, an outer protector mounted on the inner protector, said outer protector including a metallic plate hingedly suspended on the inner protector, said plate having an opening therein aligned with the first-named opening, filter glasses on the plate over the second-named opening, a latch on the hood engageable with the outer protector for releasably securing said outer protector in operative position, spring means normally maintaining the inner protector in operative position, and spring means for normally maintaining the outer protector in inoperative position.

3. A head shield of the character described comprising a hood having an opening in the front thereof, a metallic frame on the hood around the opening, an inner protector comprising a glass hingedly suspended in the frame and engageable with the hood over the opening, an outer protector mounted on the inner protector, said outer protector including an opaque plate hingedly suspended on the inner protector, said plate having an opening therein aligned with the first-named opening, filter glasses on the plate over the second-named opening, and means for releasably securing said outer protector in operative position.

WILLIAM T. COCKRILL.
THOMAS J. DUNCAN.
